UNITED STATES PATENT OFFICE.

FLORENCE BORNHAUPT, OF NEW YORK, N. Y., ASSIGNOR TO MAURICE LEVY, OF NEW YORK, N. Y.

REVERSIBLE POWDER-PUFF.

1,374,903.

Specification of Letters Patent. Patented Apr. 19, 1921.

Application filed May 26, 1920. Serial No. 384,496.

To all whom it may concern:

Be it known that I, FLORENCE BORNHAUPT, a citizen of the United States, residing at New York, in the county of New York and State of New York, have invented certain new and useful Improvements in Reversible Powder-Puffs; and I do hereby declare the following to be a full, clear, and exact description of the invention, such as will enable others skilled in the art to which it appertains to make and use the same.

This invention relates to new and useful improvements in powder puffs and more particularly to a powder puff wherein the portion which is adapted for use in applying the powder to the flesh of the user is contained in a protector when not in use so that the puff may be readily carried loose in a handbag or the like and thus prevent the powder contained in the puff from coming in contact with other articles in the bag.

A further object of the present invention is the provision of a powder puff so constructed that the part which contains the powder to be applied to the flesh of the user is arranged in a suitable protector when not in use and can be readily turned inside out so as to bring the powder puff into instant use when desired and when not in use will be disposed within the container and thus prevent any germs or other contamination from coming in contact with the puff when not in use.

A further object of the present invention is the provision of a powder puff wherein the material by which the powder is applied to the flesh of the user is contained within a protector and connected therewith in such a manner that when the powder puff is not in use, the protector will entirely inclose the material of which the puff is constructed and when it is desired to use the same, the protector and puff is turned inside out so as to expose the puff upon the exterior of the protector and when not in use, the puff is entirely contained within the protector to preserve the same and also to prevent the powder contained therein from coming in contact with various articles with which it may be associated.

With the above and other objects in view, the invention consists in the novel features and construction, the combination and arrangement of parts hereinafter more fully set forth, pointed out in the claims and

shown in the accompanying drawings, in which—

Figure 1 is a detailed perspective view of a powder puff constructed in accordance with my invention, illustrating the same in a partially opened condition,

Fig. 2 is a perspective view illustrating the puff turned inside out, ready for applying powder to the flesh of the user, and

Fig. 3 is a transverse sectional view of the device showing the powder puff entirely contained within the container.

Referring now more particularly to the drawings, the letter *a* indicates the body or protector of my improved powder puff, which is herein illustrated as formed in two separate sections of substantially circular form and sewed together for the greater part of their circumference as illustrated at *a'*. This body or protector *a* may be formed of any suitable material such as silk, satin or the like and the free edges thereof which form the opening to the interior of this body are doubled upon themselves and stitched together as shown at *e*, thus providing a suitable binding for the free edges of the body. Arranged within the body of the protector is the powder puff which includes in its construction, opposed members *b*, formed of any suitable material desirable for the purpose and of substantially the same shape as the protector. The circumferential edges of the sections of the puff are sewed together for a greater portion of the circumference the same as the protector and the puff sections are further provided with a lining *c* secured thereto and arranged upon the outside of the puff sections *b* and disposed between the puff sections and the protector *a*. This lining *c* is used particularly to secure the puff sections to the outer sections of the body in case the puff sections should be of such material that they could not be readily secured to the outside of the body by sewing or the like. The puff sections can first be attached to the lining *c* and then through the medium of the lining attached to the body of the puff, in case the puff sections should be formed of loose material which could not be readily sewed to the outside casing. It will be noted that the edges of the puff sections *b* are sewed to the edges of the protector *a* so that when the protector is turned inside out, the puff sections *b* will be likewise turned inside

105
110

out so that the opposed faces of the puff sections will be arranged upon opposite sides of the protector when turned inside out as illustrated in Fig. 2.

5 In order to protect the seam or connection between the puff sections and the protection at each end of the opening, suitable reinforcing gores *f* are provided and suitably stitched or otherwise secured to the protector 10 and the puff sections as illustrated in Figs. 2 and 3, so that in turning the device inside out and returning the same to its normal position, it will release the strain from the stitches at this point and thus provide for a 15 longer wearing quality.

The edges of the puff section at the point of opening are secured to the edges of the opening in the protector by means of a binding strip *d*, the outer edges of which are 20 folded upon themselves and stitched, or otherwise secured, to the folded edges *e* of the protector. The inner edges of these strips *d* are stitched to the edges of the puff sections *b* at the free edges thereof, as 25 illustrated in Fig. 3, so as to suitably connect the opening of the protector with the opening of the puff sections.

In Figs. 1 and 2, the letter *g* indicates the opening of the powder puff section and it 30 will be noted that when the puff sections are

contained within the protector *a*, the puff may be readily carried in a handbag or the like and thus protect the other articles in the bag with which the puff is associated from coming in contact with the powder of 35 the puff sections and the protector will also preserve the puff sections from being contaminated with germs or the like, so as to prevent them from being brought into contact with the flesh of the user. 40

What I claim is:

1. A device of the class described, including a protector, puff sections normally arranged within said protector, a lining member disposed between the walls of the protector and the puff sections, means for connecting the puff sections to the protector and reinforcing gores connected to the puff sections and portions of the protector as and for the purpose set forth. 45

2. A device of the class described, including a protector, puff sections normally arranged therein, lining portions for said puff sections to connect the same to the protector whereby said protector and puff sections may be turned inside out to expose the puff sections upon the exterior of the protector for use. 50

In testimony whereof I affix my signature.

FLORENCE BORNHAUPT.
